US00D445323S

(12) **United States Design Patent** (10) Patent No.: **US D445,323 S**
Arns (45) Date of Patent: ** Jul. 24, 2001

(54) **STAPLER**

(75) Inventor: **Stefan Arns**, Stenkullen (SE)

(73) Assignee: **Isaberg Rapid AB**, Hestra (SE)

(**) Term: **14 Years**

(21) Appl. No.: **29/122,383**

(22) Filed: **Apr. 27, 2000**

(30) **Foreign Application Priority Data**

Oct. 28, 1999 (DE) 499 10 181

(51) LOC (7) Cl. **19-02**

(52) U.S. Cl. **D8/50; D8/49**

(58) Field of Search **D8/49, 50; D19/72; 227/120, 126, 127, 128, 130-132, 134, 156**
